ADAPTER FOR PUSH AND PULL JACKS

Edmund Pachowicz, Chicago, Ill., assignor to
Templeton, Kenly & Co. Limited, Chicago, Ill.,
a corporation of Illinois

Application November 25, 1932, Serial No. 644,253

6 Claims. (Cl. 254—100)

This invention relates to improvements in adapters for push and pull jacks, and it consists of the matters hereinafter described and more particularly pointed out in the appended claims.

5 Push and pull jacks which are almost universal because of the many uses to which they may be put, include a screw member having oppositely threaded ends and associated with each end is a nut of peculiar construction; the screw member 10 being formed at a point between its ends with a means for turning the same. The nuts which are of a relatively small area are each so constructed that suitable extension bars and chains may be attached thereto to push certain spaced parts 15 away from each other or to pull the same toward each other. Such jacks have found favor in straightening vehicle frames, bodies, fenders and axles and for many other repair jobs. Because of the small area occupied by each nut, the use 20 of a push and pull jack as a lifting jack has been a limited one if at all.

One of the objects of the present invention is to provide a means whereby a jack of the kind mentioned may be readily converted into a lifting 25 jack, capable of standing upright alone and moved from one place of use to another without toppling over.

Another object of the invention is to provide 30 an adapter for a jack of this kind which may be readily applied to and removed therefrom so that the jack is universal in the many uses to which it may be put.

Still another object of the invention is to provide 35 an adapter base which is provided with means to receive either nut of the jack and which base includes parts for detachably locking the nut and base together so as to convert the jack into a lifting jack.

These objects of the invention, as well as others, 40 together with the many advantages thereof, will more fully appear as I proceed with my specification.

In the drawing:

Fig. 1 is a perspective view of an adapter embodying my invention when in position with respect 45 to a push and pull jack providing such a base therefor that the jack will stand alone and may be used as a lifting jack; and

Fig. 2 is a longitudinal sectional view through 50 the adapter and one end of an associated push and pull jack as taken on the line 2—2 of Fig. 1.

Fig. 3 is a detail horizontal sectional view through a part of the jack as taken on the line 55 3—3 of Fig. 1.

Referring now in detail to that embodiment of

the invention, illustrated in the accompanying drawing:

1a indicates as a whole a jack of the kind now known as a push and pull jack, because in connection with certain accessories, such as chains and extension bar, said jack may be actuated to exert a pressure, pulling two spaced elements toward each other, or pushing such elements away from each other. As an example of such elements, the side frame members of a vehicle chassis are mentioned, it being apparent that such frame members, because of accidents are often sprung or bent toward or away from each other.

Said jack comprises a screw member 1 having oppositely threaded end portions 2—2 and a ratchet wheel 3 midway between said end portions upon which is rotatively mounted a pawl carrying member 4. Said member 4 includes a laterally extending socket 5 for receiving an operating lever 6 by which the member 4 may be turned in the desired direction. Near said socket 7 said member 4 is provided with a spring pressed pawl 3a that is bevelled off at one side of its ratchet wheel engaging end. The other end of said pawl is provided outside the member 4 with a knob 7 whereby the pawl may be withdrawn and then turned about an angle of 180°. When the knob is released, the pawl springs back into operative engagement with the ratchet wheel. By means of this arrangement, the pawl may be caused to operatively engage the ratchet wheel for turning the same step by step in either direction; the pawl merely clicking over the teeth of the pawl in the other direction in the back and forth movement imparted to the lever. Thus the screw may be turned step by step in the proper direction, by means of the lever.

Upon each threaded end of the screw, an internally threaded nut 8 is mounted and as both nuts are of the same construction and are reversible end for end and are also interchangeable, a description of one will suffice for both. Each nut includes an internally threaded block-like body 9 provided at one end with laterally spaced enlargements 10—10 arranged to define a recess 11 in the associated end of the nut about a part of the associated end of the screw 1. In said enlargements are aligned transverse openings 12 which may open into the recess 11. Near the other end of said body in the plane of and facing 105 toward said enlargements are hook shaped lugs 13—13 and on said other end of the body are lugs 14 and 15 respectively, arranged in a plane at a right angle to the plane of said enlargements 10 and hook lugs 13 respectively, said lugs 14 and 15 110

facing in opposite directions. The enlargements 10 and lugs 14 and 15 have flat ends formed to provide slip resisting faces.

It is apparent that with the enlargements 10 facing away from each other or toward the extremities of the associated screw ends, when said flat end faces are engaged between parts to be spread away from each other and when the lever 6 is actuated to turn the screw in one direction, 10 this will cause said nuts to travel outwardly on the respective screw ends to push said parts away from each other.

The nuts may be removed from the respective screw ends and interchanged to a reverse position 15 wherein the enlargements 10 of one nut face the enlargements 10 of the other nut and likewise the hook lugs 13 of one nut will face those on the other nut. Thus if it is desired to pull certain spaced parts toward each other, a chain is passed 20 around each part and then the ends of each chain are hooked onto the lugs of an associated nut. When the screw 1 is turned in the proper direction by means of the lever 6, the nuts are caused to travel toward each other on their respective 25 ends of the screw and exert a pull on the chains attached to the lugs 13 of the nuts.

As the enlargements 10 of the nuts present but a relative small area, it is apparent that it is somewhat difficult to make the jack stand upright 30 upon one of the nuts as a base and especially upon a surface having an inclination. To make such a jack usable as a lifting mechanism capable of standing upright upon a base of sufficient area, I provide the following:

35 16 indicates a flat and preferably rectangular base plate of an area substantially greater than that presented by the flat faces of the enlargements 10 of a nut 8. Said base plate is provided at a suitable point well within its marginal edges with an opening 17 of a diameter slightly greater than that of the screw 1 and on the top side of 40 said plate about said opening is a tubular boss 18. This boss is of an outside diameter approximating that of the recess 11 in either nut and is of a height approximating the depth of said recess.

On one end of the plate and rising from the top side thereof is a horizontally disposed boss 19 in which is located a spring pressed locking plunger 20. Said plunger is arranged a distance above the 50 top of the plate corresponding to the distance between the flat end faces of the enlargements 10 of a nut and the openings 12 therein.

Said plunger includes a bolt body 21 having a head 22 at one end of a diameter approximating that of an opening 12 and on the other end of said 55 stem outside the boss 19 is provided a knob 23. A spring 24 surrounds the bolt body 21 between the head 22 and outer end of the boss 19 and normally acts to project the bolt plunger inwardly toward the boss 18. Preferably the plate is made as a forging for strength, and so that the boss 19 may be drilled from its inner end to receive the bolt 21, recesses 25 are provided in both sides of the tubular boss in line with said bolt recess in 60 the boss 19.

When it is desired to employ the jack as a lifting device, the nuts are so disposed upon the screw 2 that the enlargements 10—10 of both nuts face outwardly in opposite directions. With the 70 nuts in this position the jack is arranged in a perpendicular position, when the bottom nut is placed down upon the base so that its recess 11 substantially surrounds the boss 18 and the flat ends of the enlargements 10 engage upon the top surface of the base plate. In so applying the nut,

the plunger 20 is pulled outwardly to retract the bolt head into the boss 19 and the enlargements are disposed to stand in the plane of the boss 19. When the plunger is released its head 22 will snap into that hole 12 in line therewith and this will lock the nut against being removed from and against turning with respect to the base plate.

With the top nut engaged against the part to be lifted, when the lever 6 is actuated to turn the screw 1 in the proper direction and as neither nut can turn, the screw tends to travel out of each nut and thus cause a relative movement of said nuts endwise of the screw to impart the lift desired. After manipulating the pawl 3^a, through its knob 7, a raising or lowering movement may be provided for, by swinging the lever 6 back and forth.

When it is desired to again use the jack as either a push or pull jack, the knob 23 of the plunger is grasped and an outward pull is exerted thereon to withdraw the head 22 from the opening 12 in the nut so as to unlock the nut from the base. This will permit a separation of the parts mentioned.

By means of the invention, a push and pull 100 jack may be readily converted into a lifting jack capable of standing alone in an upright position upon a base of substantial area. The base plate described is indeed simple in construction and easy to apply to and remove from an associated push and pull jack and makes it universal in its use.

While in describing the invention, I have referred in detail to the form, arrangement and construction of the various parts thereof, the 110 same is to be considered merely as illustrative, so that I do not wish to be limited thereto except as may be specifically set forth in the appended claims.

I claim as my invention:

1. In combination with a jack including a screw having oppositely threaded ends, a nut operatively engaged on each end of said screw, means for turning said screw relative to said nuts, one of said nuts having an end recess and an opening 120 arranged at an angle to the axis of said recess, a base plate having a portion to engage in said recess so as to properly position said nut on the base plate and a spring pressed plunger carried by said base plate for detachable engagement in 125 said opening when said nut is so properly positioned on the base plate.

2. In combination with a jack including a screw having oppositely threaded ends, a nut operatively engaged on each end of said screw, means for turning said screw relative to said nuts, one of said nuts having an end recess, a base plate having an opening therein and a boss on the top side of said plate about said opening, said opening being adapted to receive said screw and said boss being adapted to engage in said recess in said nut and means for detachably securing said nut and plate together against relative separation and turning.

3. In combination with a jack including a screw having oppositely threaded ends, a nut operatively engaged on each end of said screw, means for turning said screw relative to said nuts, one of said nuts having an end recess, a base plate having an opening therein and a boss on the top side of said plate about said opening, said opening being adapted to receive said screw and said boss being adapted to engage in said recess in said nut and a spring pressed plunger carried by said plate for movement in a plane at a right angle 140

to the axis of said opening for detachably securing said nut and plate together.

4. An adapter base for a push and pull jack embodying therein a flat plate-like member having an opening therein, an upstanding boss on one side of said member about said opening, a second boss on the same side of said member and means in said last mentioned boss providing a spring pressed plunger capable of movement in the plane of said plate member toward and away from said first mentioned boss.

5. In combination with a jack including a screw having oppositely threaded ends, a nut member operatively engaged on each end of said screw, means for turning said screw relative to said nuts, each nut having a recess in one of its ends, a base member having a boss on one side

thereof to be engaged by the end recess in either nut member when said nut member is engaged with said base member, and means carried by one of said members for engagement with a part of said other member to detachably secure them together against relative separation and turning.

80

6. An adapter base for a push and pull jack embodying therein a flat plate-like member having an upstanding boss on one side at a point spaced within its margins, a second boss on the same side of said member and spaced laterally from the first mentioned boss and a member in said second boss and capable of movement toward and away from the first mentioned boss, so as to position its inner end at a point between said bosses.
